Primary Examiner — Joseph Kukella*Assistant Examiner* — Lavan M. Amerson(74) *Attorney, Agent, or Firm* — Dragon Sun Law Firm, PC; Jinggao Li, Esq.(57) **CLAIM**

The ornamental design for a front bumper for an automobile, as shown and described.

DESCRIPTION

FIG. 1 is a perspective view of a front bumper for an automobile showing my new design;

FIG. 2. is a rear perspective view thereof;

FIG. 3 is a front elevation view thereof;

FIG. 4 is a rear elevation view thereof;

FIG. 5. is a top plan view thereof;

FIG. 6. is a bottom plan view thereof;

FIG. 7. is left elevation view thereof; and,

FIG. 8. is a right elevation view thereof.

The broken lines shown in the figures depict portions of the front bumper for an automobile that form no part of the claimed design.
